UNITED STATES PATENT OFFICE.

PORTR C. FOX, OF SPOKANE, WASHINGTON, ASSIGNOR TO THE FOX COMPANY, OF SPOKANE, WASHINGTON, A CORPORATION OF WASHINGTON.

AEROPLANE.

1,055,393.

Specification of Letters Patent. Patented Mar. 11, 1913.

Application filed February 3, 1912. Serial No. 675,159.

To all whom it may concern:

Be it known that I, PORTER C. Fox, a citizen of the United States, residing at Spokane, in the county of Spokane and State of Washington, have invented new and useful Improvements in Aeroplanes, of which the following is a specification.

This invention has relation to aerial craft of the heavier than air type and has for its object to equip air planes with a novel type of control whereby the ascent or descent may be regulated at will by the difference of force between two propellers arranged at different elevations and one in advance of the other. A further purpose of the invention is the provision of means whereby the engine may be disconnected from the propellers to permit the latter to come to rest while the engine is kept in motion so that in an emergency the propellers may be instantly started to cause the machine to advance and at the same time to rise by proper adjustment of the control governing the ascent of the machine.

The invention further contemplates front and rear rudders which are so connected as to admit of the machine making a short turn, and one of the rudders being so placed with reference to the propeller to prevent rotation of the air with the propeller.

The invention also contemplates a unique form of wheel base embodying front and rear wheels, one set of wheels being mounted in a manner to admit of turning the plane when the machine is running upon the surface whereby the machine is caused to rise independently of the control provided for regulating the rise and fall of the machine when in flight.

The invention consists of the novel features, details of construction and combination of parts, which hereinafter will be more particularly set forth, illustrated in the accompanying drawings, and pointed out in the appended claim.

Referring to the drawings, forming a part of the specification, Figure 1 is a side view of a flying machine embodying the invention. Fig. 2 is an end view of the machine.

Fig. 3 is a top plan view of the machine, the lower structure being omitted. Fig. 4 is a detail view of the lower rear propeller, showing more clearly the means for changing the angular position of the blades or wings.

Corresponding and like parts are referred to in the following description, and indicated in all the views of the drawings, by the same reference characters:

The machine comprises essentially an upper structure and a lower structure, the latter being suspended from the superstructure and provided with a platform or other supporting means for receiving the operator, the engine and the control. The elevated structure is surmounted by the air plane and contains the front and rear rudders. The framework of the machine may be of any light and substantial structure which is suitably braced to insure strength.

The air plane is indicated at 1 and may be of any length and width and is of such construction as to act as a parachute to insure a comparatively safe descent of the machine in the event of the engine failing to operate or when the propellers are disconnected from the engine at the will of the operator. The main ribs or bars of the machine are indicated by the numeral 2 and the braces or stays by the numeral 3. The upper forward propeller 4 is secured to a horizontal shaft 5. The lower rear propeller 6 is mounted upon a horizontal shaft 7.

The two propellers 4 and 6 are located in different horizontal planes and at opposite ends of the machine and are of such construction, so that under normal conditions they exert a like force, whereby the machine may be propelled in a straight horizontal line. A drive chain 8 connects the two shafts 5 and 7 and passes around sprocket wheels secured to said shafts. The engine is indicated at 9 and may be of any type commonly employed for driving airships. A drive chain 10 connects the engine shaft 9 with a sprocket wheel 11 loose upon the shaft 7. A clutch 12 having a feather and spline connection with the shaft 7 is adapted

to be thrown into and out of engagement with the sprocket wheel 11 and is operated by means of a lever 13 within convenient reach of the operator. By disconnecting the clutch 12 the engine is permitted to run free without imparting any movement to the shaft 7 or to either of the propellers 4 or 6.

The front rudder 14 is located in advance of the front propeller 4 and close thereto so as to prevent rotation or churning of the air in advance of the propeller 4. The rudder 14 is arranged vertically and intermediate of the longitudinal edges of the plane 1. The rear rudder 15 is likewise arranged in a vertical plane and is approximately about twice the width of the rudder 14. The two rudders 14 and 15 are mounted to turn about vertical axes and their shafts are provided with cross bars 16 and 17 which are connected by crossed wires or cables 18, whereby the rudders 14 and 15 when turned may assume opposite angles, thereby enabling the machine to make a short turn. An operating lever 19 has connection with one of the wires or like parts 18 so that both rudders 14 and 15 may be simultaneously moved when the operating lever 19 is actuated. The superstructure comprises a platform 20 which receives the engine and the operator and to which the wheel base is attached, said wheel base comprising front wheels 21 and rear wheels 22, both sets of wheels being cushioned by suitable springs or buffers to compensate for shock. The front wheels 21 are adapted to be raised or lowered for the primary purpose of tilting the plane 1 so as to rise from the ground after the machine has acquired a proper momentum in the initial run. An operating lever 23 has connection with the front wheels 21 and by proper manipulation thereof the front wheels may be raised or lowered at the will of the operator.

The lower rear propeller 6 comprises adjustable wings which may be moved to present a greater or less effective surface for the action of the air whereby when the propeller is driven at a given speed its effective force may be varied. An operating lever 24 has connection with a sliding collar 25 mounted upon the shaft 7 and which collar is connected with the wings of the propeller to admit of adjustment thereof. When the lever 24 is operated the wings of the propeller 6 are turned to a greater or less angle, thereby offering more or less resistance to the air and consequently varying the power of the propeller. When both propellers 4 and 6 generate a like force the machine is driven straight ahead, but when the wings of the propeller 6 are adjusted so that said propeller operates with a greater force than the propeller 4 the lower portion of the machine is driven ahead so as to tilt the plane

1 and thereby cause the machine to rise, the rapidity of the ascent being regulated by varying the force of the propeller 6. After the machine has reached the desired elevation it is driven horizontally by adjusting the propeller 6 so that both propellers 4 and 6 operate with a like power.

The several operating levers 13, 19, 23 and 24 extend within convenient reach of the operator and each is provided with the usual hand latch and notched bar for holding it, the lever, in the adjusted position. When starting the machine the clutch 12 is moved to free the engine after which the latter is started and when the engine has acquired proper speed the clutch 12 is moved to throw the engine in gear, thereby operating the propellers 4 and 6 so as to drive the machine over the surface. When the machine acquires the proper speed the lever 23 is operated to depress the front wheels 21, with the result that the front end of the plane 1 is elevated and a continued forward movement of the machine causes it to rise. After the machine has left the ground its ascent is controlled by means of the lever 24, which changes the inclination of the wings of the propeller 6 to cause the latter to operate with a greater or less force to tilt the plane 1 to a greater or less angle so as to regulate the ascent of the machine. When it is required to descend the clutch 12 is shifted to disconnect the engine when the machine will drop gradually after the manner of a parachute. It is noted that the engine although out of gear is nevertheless free to operate and should occasion require the speed of the engine may be accelerated and the clutch 12 thrown into action to start the propellers to cause the machine to again rise or to move forward to clear a dangerous place. By having the plane 1 located at the top of the machine and the weight at the base the stability of the machine is assured, thereby preventing overturning.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claim appended hereto.

Having thus described the invention what is claimed as new, is:

In a flying machine, upper and lower propellers located the one at the front and

the other at the rear of the machine, means for driving the propellers at a given speed, and means for changing the angle of the blades of the lower rear propeller whereby its effective force is varied to govern the ascent of the machine when in flight by causing the machine to tilt.

In testimony whereof I affix my signature in presence of two witnesses.

PORTER C. FOX.
